UNITED STATES PATENT OFFICE.

CHARLES E. McDONALD, OF BUTTE, MONTANA.

CONTROLLING MECHANISM FOR MINE HOISTING-ENGINES.

1,188,292.

Specification of Letters Patent. Patented June 20, 1916.

Application filed April 1, 1915. Serial No. 18,552.

To all whom it may concern:

Be it known that I, CHARLES E. McDONALD, a citizen of the United States, residing at Butte, in the county of Silverbow and State of Montana, have invented certain new and useful Improvements in Controlling Mechanisms for Mine Hoisting-Engines, of which the following is a specification.

This invention relates to improvements in controlling mechanisms especially adapted for mine hoisting engines and somewhat analogous to the type disclosed in Patent Number 1,127,183 granted February 2, 1915 to A. W. Charles and myself, excepting that it is designed to operate, instead of wholly mechanically, through the intermediary of electric action.

It may be further stated that the main object in view of this apparatus is to most adequately eliminate the human liability to error by misapplication of one or more of a large number of manually operated levers by which devices of this character are controlled, as well as prevent operation of the hoisting cages beyond a point of safety.

More particularly my aim has been to provide for automatic application of the brake instrumentalities whenever there is a failure on the part of the engineer to apply the brake at the proper time, or a breakage of the main engine clutch, or yet an excess of speed of the hoisting cages, including in carrying out the invention, electric controlling members coacting with the lever controls which establish an interlocking action preventing the manipulation of any one of the same at an improper time or without having first executed a necessary preliminary setting; in other words, for example, guarding against inadvertent release of the gravity brake when the main engine clutch is disengaged or the disengagement of the engine clutch when the brake is released.

These and such other objects as may hereinafter appear are attained by the novel construction, combination and arrangement of parts to be hereinafter specifically described and claimed.

Reference will now be had to the accompanying drawings forming a part of this specification, wherein:—

Figure 1 is a front elevation of an apparatus embodying the features of my invention; Fig. 2 is a side elevation partly broken away and partly in section to show more

clearly the details of construction; Fig. 3 is a general plan view of the apparatus; Fig. 4 is a side elevation of the brake engine and pressure cylinder used in carrying out these specific improvements; Fig. 5 is an enlarged view in elevation of the traveling governor forming one of the features of this device and its electrically controlled contact instrumentalities coöperating therewith; Fig. 6 is a view looking at the mechanism shown in Fig. 5 from another side; Fig. 7 is a detail plan view of the actuating means for operating the movable sections of the contact bars coöperating with the traveling governor; Fig. 8 is a detail view showing the method of connecting the ends of the contact bars with the lower end of the actuating means hereinbefore mentioned; Fig. 9 is a fragmentary plan view of the end portion of the circuit closing member operated by the traveling governor; Fig. 10 is a vertical sectional view through the pressure cylinder, showing in elevation the actuating cams for the tappet valves of this element; Fig. 11 is a horizontal sectional view taken about on the plane indicated by the line 11—11 of Fig. 10; Fig. 12 is a detail view in elevation of a circuit closing member for automatically controlling stoppage of the hoisting cages when the latter reach the top of the mine shaft; Fig. 13 is a vertical sectional view of the governor clutch; Fig. 14 is a fragmentary elevation of the reverse lever showing the circuit controlling arrangement carried thereby; Fig. 15 is a horizontal sectional view on the line 15—15 of Fig. 14; Fig. 16 is a side elevation of the brake lever of this apparatus and showing in section the interlocking member coacting therewith for preventing improper operation of said lever. Fig. 17 is a diagrammatic view of the electric circuit arrangements employed in this device. Fig. 18 is a detailed view in elevation of a modified form of operating means for the brake engine valve controlling instrumentalities. Fig. 19 is an enlarged detail end elevation of the latch means used in the modified construction shown in Fig. 18.

It will be understood by those skilled in the art to which this apparatus appertains that in engines of the double reel or drum type there are generally employed two main engines, two brake engines, one for either drum or reel, and also two clutch engines,

but the duplication of these conventional instrumentalities is not carried out in the drawings of this case by reason of the well known coöperation thereof and 5 since they do not form a part of my invention, a full complement of the lever controls for engines of this type being shown, however, inasmuch as they are essential to a proper understanding of certain 10 features of this apparatus.

Specifically describing the preferred embodiment of my apparatus, the numeral 1 designates the conventional rope drum or reel employed in connection with hoisting 15 engines of this type, said reel having a hub or hollow short shaft 2 which is connected by the chain and sprocket connection 3 to a horizontal shaft 4 mounted in suitable bearings upon the support 5. The shaft 4 carries at one extremity a bevel gear 6 meshing with a horizontal bevel gear 7 having spline connection with the vertically movable stem 8 of a clutch governor 9. It will be observed, by reference to Figs. 1 and 13 20 more especially, that the stem 8 extends into a sleeve 10 to the lower end portion of which is keyed the upper clutch element 11 of a governor clutch which constitutes a special feature of my device. The stem 8 is provided with a pin or key 12 passing therethrough and extending into diametrically opposite slots 13 of the sleeve 10 so as to 25 fixedly secure the clutch element 11 to the stem for rotation therewith but enabling a relative movement of the stem in a longitudinal direction as caused by rising action of the governor 9 in the customary manner. I preferably provide the stem 8 and the sleeve 10 each with a flange 14, 14' respectively, intermediate which is disposed an 30 expansion spring 15 designed to normally hold the stem and clutch member in normal or neutral position, such as when the 35 governor 9 is inactive.

40 By reference to Fig. 1 it will also be noted that the rope reel 1 is adapted to be driven by the main driving shaft 16 to which the reel is clutched in the customary manner, the shaft 16 carrying the crank wheel 17 45 operatively connected to the main engine not shown. It will be understood, of course, that the actuation of the shaft 16 in one direction causes upward movement of one hoisting lift or cage and downward movement 50 of a second cage in counterbalance, the reversal of the engine actuating the lifts in the opposite direction as usual. The main shaft 16 is operatively connected to a horizontal shaft 18 journaled in suitable bearings 19 beneath the support 20 by means of the chain and sprocket connection 21. The shaft 18 carries at one extremity a beveled 55 pinion 22 meshing with a corresponding pinion 23 at the lower end of a vertically disposed shaft 24 suitably journaled in the

support 20, the latter shaft carrying at its upper extremity above the support 20 the lower clutch element 25 adapted to coöperate with the upper clutch element 11 in a manner to be more clearly described herein- 70 after. It will be noted by reference to Fig. 13 that the upper clutch element comprises two sections, the upper one 11', as hereinbefore stated, relatively fixed to the sleeve 10, and a lower section 11'' connected to the 75 upper section 11' through the instrumentality of a fastening member or bolt 26 projecting upwardly into the member 11'. This fastening member 26 only loosely connects the upper clutch elements together in 80 a manner which will allow them to rotate relatively as will be set forth in the following description. Interposed between the upper and lower sections of the upper clutch element 11 is a helical spring 27, one end of 85 which is fixed to the upper section 11' and the opposite end of which is secured to the lower section. This spring, as will be apparent, is designed to hold the sections in 90 their normal or neutral position.

Surrounding the upper section 11' is a conductor ring or band 28 insulated as at 29 from its carrying section and formed at one side of the clutch with a downwardly extending projection 30. A corresponding band 31 is carried by the lower section 11'' and has formed thereon an upwardly extending projection or lug 32 disposed relatively to the projection 30 at the opposite side of the clutch. The band 31 is also insulated from its carrying section as indicated at 33 and a brush member 34 carried by a standard 35 normally extends into contact with this band and has connected thereto the terminal of an electric conductor 36 100 leading to a suitable source of electric current. In a like manner a second brush 37 coacts with the upper band 28, being carried by the standard 38 and having connected thereto the terminal of the conductor 39 105 included in the electric circuit above mentioned.

As in the case of the construction disclosed by my joint patent hereinbefore mentioned, I employ a power or pressure cylinder for controlling the application of the brake engine utilized in apparatus of this type. This cylinder in the present instance is steam operated and may be arranged at any convenient point adjacent to the mechanism hereinbefore described. The cylinder in the drawings is of a special design, and designated 40, and comprises as shown clearly in Figs. 4, 10 and 11 a piston rod 41 which is operably connected by means of the rod or link 42 to a bell crank lever 43 fixed to the stem of a four-way valve 44. One of the arms of the bell crank lever 43 is connected by a link 45 to a lever 46 carried by the stem of a two-way valve 47, 110

said valves just mentioned controlling the 5 operation of the brake engine 48 conforming in all details to the brake engine described in our Patent No. 1,127,183, excepting that the return of the valves to normal position after actuation by the power cylinder 40 is accomplished manually through an independent lever 49 connected operatively through the bell crank 50 to an arm of the 10 lever 43 of the four-way valve 44. This return action in the previous patent was accomplished by means of certain link members connected to the brake lever of the apparatus. The rod 42 in my present arrangement is provided at its extremity connecting to the link 43 with a slotted portion so that the piston 41 of the power cylinder 40 may return to its initial position for 15 operation after actuation of the four-way valve 44, the reason for which will be more clearly understood as this description proceeds.

As above premised, the power cylinder 40 is of special construction and will now be 20 specifically described in order that the operation of this apparatus may be most clearly understood. The piston rod 41 is carried by the piston 51 adapted to reciprocate in the cylinder and above the cylinder 25 is reciprocally mounted in a suitable casing 52 the piston valve 53. The valve 53 comprises the piston head 54 at one end of the stem 55 and a corresponding piston head 56 at the other extremity of said stem. The 30 latter element is slotted as indicated at 57 and through this slot extends a guide bar 58 designed to prevent the accidental rotation of the piston within its chamber. At 35 59 is designated a steam supply pipe one branch of which leads to the intake and exhaust passage 60 at one end of the cylinder, while its other branch leads to a corresponding intake and exhaust passage 61 at the opposite end of the cylinder. The 40 piston valve casing 52 has arranged in one end a tappet valve 62 the stem 63 of which projects outwardly through the casing and has formed thereon a locking lug 64 shown most clearly in Figs. 10 and 11 of the drawings. The opposite end of the casing 52 contains a self closing tappet valve 65 similarly provided with an outwardly projecting stem 66, the stem having connected to its outer extremity one end of an actuating 45 lever 67 pivoted intermediate its length on a bracket 68. The lever 67 projects laterally from the valve casing 52 and is designed to operate the tappet valve 65 in the manner to be described hereinafter. Located at a 50 convenient point adjacent the first mentioned end of the valve casing 52 and on the cylinder 40 is an electro-magnetic solenoid 69 connected to one end of a latch bar or member 70, the other end of which bar 55 is pivotally mounted upon a bracket 71. This bar is normally engaged by the lug 64 of the stem 63 carrying the tappet valve 62, said valve in the normal position preventing access of the steam or pressure medium from the supply pipe 59 to the piston 70 valve 53. Furthermore it is to be noted that the magnet 69 is arranged in the electric circuit including the conductors 36 and 39 leading to the brushes 34, 37. As shown in Fig. 10 the piston rod 41 carries a vertically 75 disposed supporting arm or bracket 72 and secured to the upper end of this arm is a longitudinally arranged rod 73 supported at its opposite end in a guide arm 74 secured to the cylinder 40. This rod 73 carries adjacent one end an adjustable projecting cam 75 which is adapted to coöperate with the tappet valve stem 63 lying in the path of movement of said cam as will be presently disclosed. The rod furthermore carries a second cam projection 76 likewise designed to coöperate with the lever 67 connected with the tappet valve stem 66.

Describing the operation of this phase of my mechanism, and bearing in mind the foregoing description, it will be understood that so long as conditions remain normal the hoisting apparatus of this invention operates after the manner of the usual hoisting engines, but should there be a breakage 95 of the main engine clutch, the rope reel or drum will obviously move at a different relative speed to the driving shaft 16. Since one of the governor clutch elements, namely the upper, is connected to the rope reel 100 while the lower of the clutch elements is connected to the engine shaft 16, it will be apparent that through the variation of speed caused by slipping or breaking of the main engine clutch there will be a differential movement of the aforesaid clutch elements. The upper clutch element actuated by rotation of the governor from the rope reel is brought into contact with the lower clutch element when the governor balls rise 110 and force the governor stem downwardly carrying the two sections of the upper clutch member. The variation or differential movement of the operating parts as above mentioned, however, causes the top 115 section of the upper clutch member to rotate relatively to the lower section which is in firm frictional contact with the lower clutch element, such relative rotation causing the lug or projection 30 of the band 28 on the upper section to contact with the lug 32 of the lower section, closing the circuit through the conductors 36, 39 to the electro-magnet 69, and in turn the lever or link 70 coöperating with the magnet is raised upwardly. Since pressure is normally exerted upon the tappet valve 62 by steam from the supply pipe 59 passing through the by-pass 77 immediately the tappet valve is 125 released, its movement toward the left oc- 130

curs allowing the steam to pass into the piston valve casing causing said piston valve to move toward the right until the passage 60 is brought into communication through 5 the piston head 54 with the supply pipe 59, whereupon the piston 51 is moved toward the right of its cylinder, in turn causing an actuation of the connecting link 42 which thereupon operates the four-way and two- 10 way valves of the brake engine 48, finally causing an application of the brake.

In the movement of the piston 51 as just described the arm or cam 75 is brought into contact with the tappet valve 71 automatically 15 retatching this valve in its inoperative position. Simultaneously the cam or arm 76 coacts with the upturned extremity 67' of the tappet lever 67 moving the tappet valve 65 to the left and admitting pressure 20 against the piston valve 53, which in turn brings the supply passage 59 into communication with the passage 61, admitting pressure against the piston 51 for moving the latter back to its initial or normal position. 25 The return of this piston to the normal position ready for subsequent action does not act upon the brake engine, due to the slotted formation of the extremity of the rod 42 as disclosed by Fig. 4. As also shown in this 30 figure a signal bell 78 is arranged so that the engineer is given a warning when the mechanism goes into action.

Since the breaking of the engine clutch or slipping of the same, the misapplication of 35 the engine levers (releasing the clutch while the brake is disengaged or releasing of the brake when the clutch is disengaged) or even the rendering inoperative of manipulating connections between the brake lever 40 and the valve connections of the brake engine while the clutch is disengaged, all cause or bring about a variation of movement of the governor clutch elements hereinbefore described; the automatic setting of the brakes 45 is accomplished through the various instrumentalities just discussed.

The control for governing the speed of the operation of the hoists will now be described. Intermediate the length of the 50 horizontal shaft 4 is located a pinion 79 meshing with a miter gear 80 at the upper end of a shaft 81 carrying a traveling governor 82 which is caused to move upwardly and downwardly, in accordance with the 55 movements of the skips, on the spaced screw shafts 83. These shafts are operatively connected by the sprocket chain 84 and are driven through the worm and gear connection on the shaft 4 as indicated at 85. The 60 governor is supported and rotates on the double connecting nut 86, the latter carrying a laterally projecting arm 87 (see Fig. 5) which in turn pivotally supports a bell crank lever 88 one arm of which is connected to the governor 82 while its other arm has

pivotedly connected to it a contact carrying rod or bar 89 slidingly mounted in the bracket 87'. As shown in Fig. 9 this bar carries at its outer end a primary contact member 90 of spring material, preferably, 70 and a secondary contact member 91 spaced therefrom. Suitably supported adjacent to the traveling governor 82 are a pair of spaced outer contact bars vertically disposed, as designated at 92, of magnetic steel 75 of slender yet rigid structure. Each of these bars has upper and lower pivoted sections 93, 94 inclined inwardly from the vertical normally, as best seen in Fig. 5, said bars being arranged in an electric circuit including the source of power or battery 95 and the signal bell 96. Also located adjacent to the contact member 89 are a pair of inner vertical contact bars 97 spaced farther apart from each other than the corresponding bars 85 92 in order to enable movement of the outer contact member 90 therebetween, said bars being similarly provided with upper and lower pivoted sections 98, 99. These last mentioned bars are arranged in a circuit including the battery 100, the circuit leading to and also including the electro-magnet 69 on the power cylinder hereinbefore mentioned. Now the object and functions of this control mechanism or governor is to 95 accomplish an automatic adjustment in the event of overspeeding or unwinding, as well as provide for two positive stops of the hoists at upper and lower landings. The vertical portions of the spaced bars aforesaid represent the central portion of the mine shaft, where the speed of the cages is much greater than when approaching the top or bottom. Therefore, it will be seen that when the main engine is running up to 100 the desired full speed the centrifugal action on the governor 82 will move the bell crank 88 on its pivot, transmitting its motion to the bar 89 which in turn carries the circuit closing member 90 close to the outer bars 92. Should the speed slightly increase the member 90 is brought into contact with the bars 105 and the signal bell is sounded, warning the engineer that he has reached the safety limit of speed. If a still further increase of speed takes effect for any reason whatever the bar 89 is moved outwardly a greater distance until the circuit closing member 91 contacts with the bars 97, closing the circuit leading to the magnet of the power cylinder, releasing this power applying instrumentality, setting the brakes and stopping the engine. The inclined sections of the contact bars represent the portion of travel of the cages 110 when they approach the top and bottom respectively of the shaft, and where necessarily the speed must be reduced. Obviously unless the engineer reduces the speed of travel as these sections of the bars are 115 reached the brakes will be applied but de- 120 125 130 135

crease of speed will be followed by a corresponding retraction of the bar 89 permitting normal movement of the cages in the desired manner. I preferably provide, however, a 5 positive contact adjacent to the top and bottom of each contact bar section 89, 99 as indicated at 101, 102 so that when the cage or skip has ascended or descended slightly beyond its extreme landing positions, the circuit 10 closing arrangement of the traveling governor immediately closes the circuit to the electro-magnet of the power cylinder, causing application of the brakes and stopping of the engine.

15 In practical operation of mining hoists it is always desirable to begin the ascending or descending movements of the cages at much greater speed than at their termination. In order to enable this to be accomplished it is 20 requisite that the deflecting portions of the contact bars be moved to aligned position with the vertical portions, or approximately so, and for this purpose I provide a vertical rod 103 (see Fig. 5) supported adjacent to 25 the shaft of the traveling governor 81 with spaced crank segments, the upper 104 and the lower 105. The former is connected by the link 106 to a second crank disk 107 at the top of a vertical rod 108, the lower end of 30 which has a similar disk 109, connected in turn by the link 110 to the upper ends of the upper contact bar sections 93, 98. The lower segment 105 is likewise connected by the link 111 to the disk 112 carried by the vertical 35 rod 113, its lower disk 114 being connected to the lower contact bar sections 94, 99 by the link 114'. The connection of the links 110 and 114' to their cranks is best disclosed by the illustration in Fig. 8 where the 40 operative connection is established by means of a pivoting arrangement 114" consisting of non-conducting material or insulation.

The segments 104, 105 lie in the path of movement of the roller 115 which is carried 45 upwardly and downwardly and rotated with the governor shaft by the governor 82. As the cage ascends this arrangement will operate to hold the upper movable sections 50 of the contact bars in deflected position but immediately the cage descends the sections are moved to vertical position through operation of the roller 115 on the proper segment with which it has self-adjusting frictional contact. By the above described arrangement 55 the engine may attain the limit of speed much more quickly than if the inclined portions were fixed.

The next important feature of my invention relates to the interlocking arrangement 60 for the control levers by means of which an automatic control is exercised over the engineer's actions with respect to the operation of these elements. In Figs. 1, 2 and 3 it will be seen that the shaft 4 is operatively connected by means of a chain and sprocket

mechanism 116 to a shaft 117 extending laterally of and preferably beneath the lever platform 118. The opposite end of the shaft is journaled in a standard 119, as disclosed most clearly by Fig. 12 illustrating the timing arrangement of this device. The shaft 117 is formed with a worm 120 for actuating the worm gear 121 carried by the vertical screw shaft 122 journaled for rotation to cause a traveling nut 123 having threaded 70 connection therewith to move upwardly and downwardly in conformity with the travel of a cage of the hoisting apparatus, of course in proper ratio to its movement. The nut 123 is guided by the post 124 and also cooperates with a rotatable contact member 125 feathered on the shaft 122. The movement of this nut 123 and the member 125 is so timed that as the cage approaches the top of the mine shaft the member 125 will reach 80 the top of the shaft 122, at which point it will impinge the lower of a pair of yieldable circuit making members or jaws 126 suitably supported beneath the platform 118, the yieldable members being insulated 85 from each other. These jaws are included in an electric circuit, the wires 127 of which lead from the battery or source of power 128 to a solenoid 129 (see Fig. 16) disposed just in advance of the brake lever 130 at one end 90 of the platform 118. Now, for illustration, we shall suppose that a cage or skip is at the thousand foot level or landing and the engineer proceeds to pull the same to the surface or uppermost landing. As the cage 100 moves upwardly this worm gear and screw with its traveling nut and contact goes into action, the nut moving upwardly and carrying the circuit making member which is so timed as to arrive at the jaws 126 as the cage 105 reaches the upper landing. When the member 125 contacts with the jaws 126, forcing them together, the circuit is closed and the solenoid 129 is shot upwardly through an opening in the casing 131 in which is slida- 110 bly mounted a block 132 connected by a link 133 to the brake lever 130, said block having an opening therein also in which the solenoid moves as the brake lever is moved into the position shown in full lines in Fig. 16, 115 setting the brakes. Therefore it follows that before the brakes can be released in the further operation of the hoisting apparatus the brake lever 130 must be unlocked and this is accomplished by providing the usual 120 reverse lever of the hoisting apparatus designated 134 with a circuit breaking element at its lower end, consisting of a strip of non-conductive material or insulation, 135, which when the reverse lever is moved to the left 125 from its position in Fig. 14 will be projected between the circuit making strips 126, breaking the circuit and allowing the solenoid to drop from its locked position in the block 132 connected to the brake lever. 130

Thus the engineer has been obliged to reverse before releasing the brake and opening the throttle, the throttle lever being designated 136 in Fig. 1, and hence the likelihood 5 of accidental movement of the uppermost cage into its sheaf is eliminated. As customary, there are two brake levers, the second being indicated at 130', as well as two clutch levers 137, 137', one for each brake engine 10 and clutch engine, required for the two drums or reels employed, and the foregoing lock arrangement is provided for each brake lever.

It will be observed by reference to Fig. 14 15 that the reverse lever carries still a further contact or circuit making device shown above that just described and designated 138. This contact arrangement is included in a separate and distinct circuit 139 leading 20 to the source of power 140 and a solenoid 141 arranged as will be noted in Fig. 1 of the drawings to coact with the clutch lever in the exact manner disclosed with respect to the interlocking arrangement of 25 the brake lever shown in Fig. 16. On account of the similarity the specific instrumentalities will not be described other than to state that the member 138 is a circuit closing member which upon movement of 30 the reverse lever in one direction will be introduced between the terminals 142 of the circuit 139 closing the circuit and actuating the solenoid to lock the clutch lever in its engaged position. This circuit works in 35 conjunction with a second circuit, indicated 143 in Fig. 16, also leading to the clutch lever solenoid, the circuit 143 being closed by the brake lever 130 at 143' when it is moved into dotted line or release position 40 shown in the figure mentioned. In further explanation of this arrangement it may be noted that when the engine is running or hoisting the cage or skip, the engine clutch must be engaged, also the reverse lever must 45 be in its proper position with the brake lever in the release position. The reason for closing the circuit both from the reverse lever and the brake lever to the clutch lever lock is due to the fact that sometimes it occurs 50 that the engineer while operating both drums collectively allows the main engine to attain the overspeeding stage, when he finds it more desirable to reverse his engine in order to reduce the speed than to apply the 55 brake. It is quite obvious then that if this clutch lever were locked only by the reverse lever movement when in the correct hoisting position, the movement of the reverse lever into reversing position would unlock the 60 clutch member and thereby make it possible for a misapplication of the lever control as is quite often the case.

In the double hoisting engine type with two reels or drums it is comprehended to 65 employ two timing contacts such as illus-

trated in Fig. 12 and the second of which is designated 126' in Fig. 14, for closing the brake solenoid circuits owing to the fact that there are two brake lever controls, as distinctly shown in Fig. 1 of the drawing. 70

In conclusion, a brief statement of the operation which takes place from the time the brakes are released during the entire cycle of operation will now be given. Assuming one of the cages to be at the lowermost position in the mine shaft and one at the surface or uppermost landing with all levers in correct position, and engine at rest, it will be understood both brakes are set or engaged, both engine clutches are engaged 75 and the reverse lever in correct position for raising, throttle closed,—the engineer first releases the brake on the uppermost side, then the brake on the lower, and immediately opens the throttle (the brake levers 80 having been released when the reverse lever was moved to reversing position, opening brake lock circuit). The engine now winds up the lower cage while at the same time the uppermost cage is being lowered, the 85 cages running in counterbalance. With the engine running and hoisting, the brake levers in release position, close the circuits at A, A (see Fig. 17) these designations representing the brake contacts 143' for clutch 90 lever magnets leading to the clutch lever solenoids C, C, (141, 141) thus locking both clutch levers in the engaged position while the engine is running; also the reverse lever closes its independent circuit D (142) leading 95 to the clutch lever solenoid C. Now as the cage is hoisted to its uppermost landing a timing contact designated 126 closes the circuit to the brake lever solenoids B, B, (129, 129) just prior to arrival of the cage 100 thereby locking both brake levers in the set or engaged positions, when they are manually operated to stop the cages. The next step of procedure involved is the reversal of the engine by placing the reverse lever in 105 opposite position, when by so doing it breaks the circuit to the brake solenoids B, B owing to the introduction of the member 135 between 126 unlocking both brake levers and simultaneously closing the clutch circuit at 110 D, locking clutch lever in the engaged position. The engineer at this point as in the former operation releases the brakes, opens the throttles, causing the lowermost cage to ascend while the other descends, and as both 115 brake levers are in their release position the circuits at A, A to the clutch solenoids C, C are closed and the clutch lever locked in the engaged position. As the second cage reaches its uppermost destination the timing contact operable by this cage closes and when the brakes are applied levers are locked as before.

As hereinbefore premised, there are two timing contact arrangements such as desig- 120

nated at 126 operable to close the circuits at E, E in the circuit diagram, and the reason for this is that obviously the cages are not always run in counterbalance but may be 5 operated singly as well. The reverse lever contact, it may also be noted, does not lock both clutches at the same time but closes the circuit and locks only on the side that is being raised or hoisted. Also the brake levers 10 in the release position do not lock the clutch levers collectively but either brake lever in its release position will lock the clutch lever for its respective side. Hence when running counterbalanced both clutch levers are 15 locked, both brake levers being in full release and in operating the drums or cages singly the reverse lever closes the circuit to the clutch solenoid on that single side and the brake lever in the release position closes 20 the circuit at the same time.

In further explanation of the wiring diagram of Fig. 17 when the governor clutch circuit is closed at F it operates the power cylinder solenoid or magnet indicated at G 25 and the warning signal device G'. The circuit closing arrangement of the inner contact bars is indicated at H and when this circuit is closed by means of the contact bar 89 carried by the traveling governor 82 the power 30 cylinder magnet G and the warning signal G' are also operated. The circuit closing arrangement for the outer contact bars is designated at I and when the circuit is closed at I by means of the contact member 89 on 35 the traveling governor the alarm signal indicated at J is sounded.

It will be apparent that changes may readily be made in the specific instrumentalities set forth in the foregoing description 40 without departing from the spirit of the invention and within the scope of the appended claims. It is comprehended by me, for instance, to employ other operating means for the brake engine than the pressure cylinder or device hereinbefore described, and such operating means may readily comprise weights which may be connected to suitable operating levers for the brake engine and released by a magnet for operating the four- 45 way and two-way valves, somewhat after the manner disclosed in conjunction with the pressure cylinder herein described. Such an arrangement is disclosed in Figs. 18 and 19 of the drawings and will briefly be described.

50 The four-way valve 44 is provided with a lever 43^a which is connected by the rod 45 to the lever 46 of the two-way valve 47 of the brake engine. A weight 200 is connected by means of a slotted link 201 to the lever 55 43^a, said weight being mounted between and guided by suitable spaced standards 202. Pivoted to one of the standards at 203 is a supporting lever 204 the lower end of which has pivotally connected thereto a link 205, in 60 turn connected at its other end to the weight

200. This lever has its upper extremity bevelled and normally engages with the pivoted tripping latch or bar 206, with the outer end of which the electro-magnet 69 coacts. This electro-magnet is the one coöperating with 70 the power or pressure cylinder 40 hereinbefore described and its action need not be further described other than to say that it is actuated in the same manner as with reference to the preferred form so that when the 75 circuit is closed it moves the trip bar 206 upwardly, releasing the lever 204 which allows the weight 200 to drop and in dropping the four-way and two-way valves 44 and 47 are operated and the brake engine thereby 80 applied. A lever 207 is disposed at a convenient position for raising the weight 200 through the rod 208 having a slotted extremity 209 coacting with a bell crank lever 210, one arm of which lever is connected to 85 the link 201 by the rod 211. Movement of the lever 207 in one direction will raise the weight and cause the lever 204 to automatically engage with the latch 206, whereupon said lever 207 may be restored to normal position by reason of the slotted extremity 209. The independent lever for applying the 90 brake engine or operating the valves 44 and 47 in this modified arrangement is the same as with reference to the preferred form, said 95 lever being indicated in Fig. 18 character 49. It will be obvious that the operation of the brake engine valves as described is independent of the weight having in view the employment of the slotted link 21 which permits the lever 43^a to move without disturbing the position of the weight.

It will be apparent from the foregoing, that both the governor controls, designated 9 and 82 are automatic in their action, the 105 former controlling application of the brake applying means in the event of slippage or breakage of the main clutch, and the latter being primarily a speed controlling instrumentality, automatically causing operation 110 of the brake applying means when the cages are operated at abnormal speeds, either between landings or as they approach landings. Moreover, it should be understood that the timing and interlocking arrangement described in the foregoing specification is automatic in its action in conjunction with the manual manipulation of the levers, said interlocking mechanism having no relation to 115 the action of the governors, excepting that the contact members 125 and 126 are controlled or timed from the sprocket chain driven from the governor shaft.

Having thus described the invention, what 120 is claimed is:

1. In apparatus of the class described, the combination of a driven shaft, a clutch member operatively connected to the shaft, a governor, a part operably connected to the shaft and adapted to drive the governor, a 125

- second clutch member operable with the governor and adapted to engage the first clutch member on actuation of the shaft aforesaid, brake applying means, operating means adapted to control said brake applying means, and means intermediate the governor and the operating means to release the latter upon differential movement of the shaft part and said shaft.
- 10 2. In apparatus of the class described, the combination of a driven shaft, a clutch member operatively connected to the shaft, a governor driven from said shaft, a second clutch member operably connected to the governor and adapted to engage the first clutch member, brake applying means, an operating device adapted to control said means, locking means coacting with the operating device normally holding the latter inactive, and 15 means intermediate the locking means and the second clutch element operable upon relative movement of the clutch members to release the operating device for actuation of the brake applying means thereby.
- 15 3. In apparatus of the class described, the combination of a driven shaft, a clutch member operatively connected to the shaft, a drum adapted to be driven by said shaft, a second clutch element operably connected to 20 the drum, brake applying means, a pressure device for controlling said means, and an electrically operated locking device coöperating with the pressure device and releasable upon relative movement of the clutch 25 elements for actuation of the brake applying means.
4. In apparatus of the class described, the combination of a driven shaft, a clutch member operatively connected to the shaft, a part 30 on said shaft adapted to be driven thereby, a governor connected to said part, a clutch member actuated by the governor and comprising relatively movable sections, brake applying means, controlling means for the latter, and means intermediate the controlling 35 means and the sectional clutch member adapted to cause actuation of said controlling means upon relative movement of the clutch sections due to relative movement of the clutch members.
5. In apparatus of the class described, the combination of a driven shaft, a clutch member operatively connected to the shaft, a part 40 on said shaft adapted to be driven thereby, a governor connected to said part, a clutch member actuated by the governor and comprising relatively movable sections, brake applying means, controlling means for the latter, circuit closing means carried by 45 the said clutch sections, a locking member coacting with the controlling means to normally hold it inactive, and an electric circuit connected to the circuit closing means and including a source of current whereby 50 on relative movement of the clutch sections the circuit is closed and the locking member actuated to release the controlling means.
6. In apparatus of the class described, the combination of a driven shaft, a clutch member operatively connected to the shaft, a part 55 on said shaft adapted to be driven thereby, a governor connected to said part, a clutch member actuated by the governor and comprising a section connected for rotation therewith and a section carried for relative movement with respect to the other section and adapted to engage the first mentioned clutch member during operation of the governor, brake applying means, a pressure cylinder controlling said means, an electrically 60 operated locking member normally holding the pressure cylinder inoperative, and an electric circuit connected to the clutch sections and the locking member and including a source of current whereby upon relative movement of the clutch members the clutch section engaging the first mentioned clutch member is caused to move relatively of its coöperating section for closing the circuit and releasing the locking member.
7. In apparatus of the class described, the combination of a driven shaft, a clutch member operatively connected to the shaft, a part 65 on said shaft adapted to be driven thereby, a governor connected to said part, a clutch member actuated by the governor and comprising a section connected for rotation therewith and a section carried for relative movement with respect to the other section and adapted to engage the first mentioned clutch member during operation of the governor, circuit closing members on said sections insulated therefrom and normally held in neutral position with respect to each other, brake applying means, a pressure cylinder controlling said means, a solenoid actuated member normally holding the latter inactive, and an electric circuit connected to the circuit closing members and the solenoid device and including a source of current whereby on relative movement of the clutch sections due to relative movement of the clutch members the circuit is closed and the cylinder released after actuation of the brake applying means.
8. In apparatus of the class described, the combination of a driven shaft, a clutch member operatively connected to the shaft, a part 70 on said shaft adapted to be driven thereby, a governor connected to said part, a clutch member actuated by the governor and comprising relatively movable sections, brake applying means, controlling means for the latter, means intermediate the controlling means and the sectional clutch member adapted to cause actuation of said controlling means upon relative movement of the clutch sections due to relative movement of the clutch members, and means for restoring the controlling means
- 120 125 130 135

to normal condition upon actuation of the brake applying means.

9. In apparatus of the class described, the combination of a driven shaft, a clutch member operatively connected to the shaft, a part on said shaft adapted to be driven thereby, a governor connected to said part, a clutch member actuated by the governor and comprising relatively movable sections, 5 brake applying means, a pressure device for the latter, means intermediate the pressure device and the sectional clutch member adapted to cause actuation of said pressure device upon relative movement of the clutch 10 sections due to relative movement of the clutch members, and means carried by the pressure device for automatically restoring said device to normal condition after actuation of the brake applying means.
- 15 10. In apparatus of the class described, the combination of a driven shaft, a clutch member operatively connected to the shaft, a drum adapted to be driven by said shaft, a second clutch element operably connected 20 to the drum, brake applying means, a pressure cylinder for controlling said means, a piston therefor, locking means for maintaining the piston inoperative, means intermediate the locking means and a clutch 25 member for releasing the locking means upon relative movement of the clutch members, valve means for said cylinder, and means automatically controlling the valve 30 means for restoring the piston to normal position.
- 35 11. In apparatus of the class described, the combination of a driven shaft, a clutch member operatively connected to the shaft, a drum adapted to be driven by said shaft, a second clutch element operably connected 40 to the drum, brake applying means, a pressure cylinder for controlling said means, a piston therefor, valve means for said cylinder, locking means coacting with the valve 45 means for maintaining the piston normally inoperative, means intermediate the locking means and a clutch member for releasing the locking means upon relative movement of the clutch members, and means carried 50 by the piston for actuating the valve means upon movement of the piston whereby to cause the latter to be restored to normal position.
- 55 12. In apparatus of the class described, the combination of a driven shaft, a rope reel adapted to be driven thereby, a clutch member, connections intermediate the shaft and said clutch member, a governor, connections intermediate the rope reel and said 60 governor, a clutch member carried by the governor for rotation therewith, said last mentioned clutch member consisting of co-operating upper and lower sections, said lower section being relatively movable with 65 respect to the upper section, circuit closing
- members carried by said clutch sections, an electric circuit connected to said clutch sections, a pressure cylinder, a piston operable therein, brake applying means, a connection intermediate the brake applying 70 means and the cylinder piston, valve means for supplying pressure to said cylinder, a solenoid actuated locking member co-operating with the valve means and normally holding the pressure cylinder inoperative, 75 said solenoid actuated member being included in the electric circuit aforesaid whereby, upon relative movement of the aforesaid clutch sections due to relative movement of the clutch members, to close 80 the electric circuit for releasing the valve means of the pressure cylinder through the solenoid actuated locking member, and means associated with the valve means aforesaid for relatching the solenoid actuated member subsequent to actuation of the brake applying means by the pressure cylinder.
- 85 13. In apparatus of the class described, the combination of a driven shaft, a rope reel adapted to be driven thereby, a clutch member, connections intermediate the shaft and said clutch member, a governor, connections intermediate the rope reel and said 90 governor, a clutch member carried by the 95 governor for rotation therewith, said last mentioned clutch member consisting of co-operating upper and lower sections, said lower section being relatively movable with respect to the upper section, circuit closing 100 members carried by said clutch sections, an electric circuit connected to said clutch sections, a pressure cylinder, a piston operable therein, brake applying means, a connection intermediate the brake applying 105 means and the cylinder piston, valve means for supplying pressure to said cylinder, a solenoid actuated locking member co-operating with the valve means and normally holding the pressure cylinder inoperative, 110 said solenoid actuated member being included in the electric circuit aforesaid whereby upon relative movement of the aforesaid clutch sections due to relative movement of the clutch members to close the 115 electric circuit for releasing the valve means of the pressure cylinder through the solenoid actuated locking member, and valve actuating means carried by the piston and movable with said piston upon release of 120 the locking member, the valve means lying in the path of movement of the actuating means and adapted to be impinged thereby for restoring the piston to normal position subsequent to actuation of the brake applying means.
- 125 14. In apparatus of the class described, the combination of a driven shaft, a rope reel adapted to be driven thereby, a clutch member, connections intermediate the shaft

and said clutch member, a governor, connections intermediate the rope reel and said governor, a clutch member carried by the governor for rotation therewith, said last mentioned clutch members consisting of coöperating upper and lower sections, said lower section being relatively movable with respect to the upper section, circuit closing members carried by said clutch sections, an electric circuit connected to said clutch sections, a pressure cylinder, a piston operable therein, brake applying means, a connection intermediate the brake applying means and the cylinder piston, a tappet valve for said cylinder for controlling pressure to be admitted thereto, a solenoid actuated member normally holding the tappet valve in inoperative position and adapted to release said valve upon closing of the circuit when the clutch sections move relatively to each other for operation of the brake applying means aforesaid, and actuating means for the tappet valve whereby to restore the piston of the cylinder to normal position, said actuating means comprising a movable cam member and a support for said member operably connected to the piston cylinder and movable therewith.

15. In apparatus of the class described, the combination of a driven shaft, a cage actuating member operable therewith, a governor driven by said member, means adjacent to the governor for controlling the movements of the cage actuating member, 30 brake applying means, operating means for controlling the brake applying means, an electric circuit in which the means adjacent to the governor are included and connected to the operating means aforesaid, and means 35 operable by the governor for coaction with the means adjacent thereto as aforesaid for causing operation of the brake applying means under excessively high speed of the cage actuating means.

40 16. In apparatus of the class described, the combination of a driven shaft, a drum adapted to be operated thereby, a governor operatively connected to said drum, contact members adjacent to the governor, an electric circuit in which said members are included and including a source of current, a 45 circuit closing member operatively connected to the governor and adapted to coöperate with the contact members, brake applying means, a controlling device for said brake applying means, and means normally holding the latter inoperative, said last mentioned means being included in the circuit aforesaid whereby upon excessive speed of 50 the drum the locking member is released and the brake applying means operated.

45 17. In apparatus of the class described, the combination of a driven shaft, a cage actuating drum adapted to be operated thereby, a traveling governor adapted to be

rotated by said drum, means for bodily moving the governor during rotation thereof, brake applying means, a pressure device for controlling said means, and means for releasing the pressure device controlled from the governor when the latter reaches an excessive speed.

18. In apparatus of the class described, the combination of a driven shaft, a cage actuating drum adapted to be operated thereby, a traveling governor adapted to be rotated by said drum, means for bodily moving the governor during rotation thereof, brake applying means, a pressure device for controlling said means, spaced contact members adjacent to the governor, an electric circuit including said members and a source of current, an electrically operated locking member included in the circuit and coöperating with the pressure device, and a circuit closing member carried by the governor normally inoperative with respect to the contact members under normal operation of the drum but adapted to be projected into contact with the contact members upon excessive speed of the governor or drum.

19. In apparatus of the class described, the combination of a driven shaft, a cage actuating drum adapted to be operated thereby, a traveling governor adapted to be rotated by said drum, means for bodily moving the governor during rotation thereof, spaced contact members adjacent to the governor, an electric circuit including said members and a source of current, a signal device included in said circuit, a circuit closing member carried by said governor adapted to coact with the contact members, said circuit closing member being inoperative with respect to the contact members during normal actuation of the governor but adapted to be projected into contact with the contact members upon reaching a predetermined limit of speed of the governor whereby to close the circuit for sounding the signal.

20. In apparatus of the class described, the combination of a driven shaft, a cage actuating member adapted to be driven thereby, a traveling governor operatively connected with the cage actuating member for rotation thereby, means for moving the governor corresponding to the movement of a cage by the cage actuating member, a warning signal, contact members associated with the governor, an electric circuit including said contact members and the signal, brake applying means, an operating device controlling said brake applying means, a second set of contact members associated with the governor, an electric circuit including said second set of contact members and the operating device aforesaid, and a circuit closing member operably connected to the governor and arranged to close the

first mentioned circuit when the speed of the governor reaches a predetermined limit, and to close the second mentioned circuit when the speed of the governor passes such limit whereby to actuate the brake applying means aforesaid.

21. In apparatus of the class described, the combination of a driven shaft, a drum adapted to be operated thereby, a traveling governor operatively connected to said drum, contact members adjacent to the traveling governor, an electric circuit in which said members are included and including a source of current, a circuit closing member operatively connected to the governor and adapted to coöperate with the contact members, brake applying means, a controlling device for said brake applying means, means normally holding the latter inoperative, said last mentioned means being included in the circuit aforesaid whereby upon excessive speed of the drum the locking member is released and the brake applying means operated, and speed controlling sections carried by said contact members for compelling reduction of speed at a predetermined point in the travel of said traveling governor.

22. In apparatus of the class described, the combination of a driven shaft, a drum adapted to be operated thereby, a traveling governor operatively connected to said drum, contact members adjacent to the traveling governor, an electric circuit in which said members are included and including a source of current, a circuit closing member operatively connected to the governor and adapted to coöperate with the contact members, brake applying means, a controlling device for said brake applying means, means normally holding the latter inoperative, said last mentioned means being included in the circuit aforesaid whereby upon excessive speed of the drum the locking member is released and the brake applying means operated, movable speed controlling sections carried by said contact members for compelling reduction of speed at a predetermined point in the travel of said traveling governor, and means for moving said movable sections from normal position to permit normal movement of the traveling governor.

23. In apparatus of the class described, the combination of a driven shaft, a cage actuating member adapted to be driven thereby, a traveling governor operatively connected with the cage actuating member for rotation thereby, means for moving the governor corresponding to the movement of a cage by the cage actuating member, a warning signal, contact members associated with the governor, an electric circuit including said contact members and the signal, brake applying means, an operating device

controlling said brake applying means, a second set of contact members associated with the governor, the electric circuit including said second set of contact members and the operating device aforesaid, a circuit closing member operably connected to the governor and arranged to close the first mentioned circuit when the speed of the governor reaches a predetermined limit and to close the second mentioned circuit when the speed of the governor passes such limit whereby to actuate the brake applying means aforesaid, movable speed controlling sections carried by each of said contact members, said sections being normally arranged to compel reduction of speed of operation of the cage actuating member at predetermined points in the travel of the governor, and means operable by the governor for moving said sections whereby to permit normal operating speed of the cage actuating member.

24. In apparatus of the class described, the combination of a driven shaft, a cage actuating drum operable thereby, a brake controlling member, a movable member operatively connected to the drum and adapted for travel corresponding to the travel of a cage connected to said drum, and means with which said movable member coöperates when the cage arrives at the approximate limit of its movement for rendering said brake controlling member temporarily inoperative when moved into brake setting position.

24. In apparatus of the class described, the combination of a driven shaft, a cage actuating drum operable thereby, a brake controlling lever, locking means for holding said lever in brake applied position, and means controlled by the cage actuating drum for causing engagement of the locking member with the brake lever in the set position aforesaid.

26. In apparatus of the class described, the combination of a driven shaft, a cage actuating drum operable thereby, a brake controlling lever, locking means for holding said lever in brake applied position, means controlled by the cage actuating drum for causing engagement of the locking member with the brake lever in the set position aforesaid, and means for releasing the lock member to permit release of the brake controlling lever.

27. In apparatus of the class described, the combination of a driven shaft, a cage actuating drum operable thereby, a brake controlling lever, a locking device associated with said lever and adapted to coact with the same when the brake lever is in set position, a circuit closing member associated with the brake lever, an electric circuit including said circuit closing member and the locking device aforesaid, and means oper-

ably connected to the cage actuating drum for closing the circuit aforesaid at a predetermined time to lock the brake lever in its set position.

28. In apparatus of the class described, the combination of a driven shaft, a cage actuating drum operable thereby, a brake controlling lever, a locking device associated with said lever and adapted to coact with the same when the brake lever is in set position, a circuit closing member associated with the brake lever, an electric circuit including said circuit closing member and the locking device aforesaid, means operably connected to the cage actuating drum for closing the circuit aforesaid at a predetermined time to lock the brake lever in its set position, and means for breaking the circuit to release the locking member and permit movement of the brake lever to release position.

29. In apparatus of the class described, the combination of a driven shaft, a cage actuating drum operable thereby, a brake controlling lever, a locking device associated with said lever and adapted to coact with the same when the brake lever is in set position, a circuit closing member associated with the brake lever, an electric circuit including said circuit closing member and the locking device aforesaid, a contact member adapted to coöperate with the circuit closing member at a predetermined time controlled by the cage actuating drum whereby to lock the brake in its set position, a releasing member associated with the circuit closing member, and a circuit breaking element carried by said releasing member and adapted to coöperate with the circuit closing member for breaking the circuit and releasing the brake controlling member.

30. In apparatus of the class described, the combination of a driven shaft, a cage actuating drum operable thereby, a brake controlling member, means for controlling reversal of the cage actuating drum, locking means coacting with the brake controlling member to lock the same in brake setting position, means for actuating said locking member, and means carried by the reverse controlling member for releasing the brake controlling member after actuation of the reverse controlling member.

31. In apparatus of the class described, the combination of a driven shaft, a cage actuating drum operable thereby, a plurality of controlling instrumentalities associated therewith including a brake lever, a reverse lever and a clutch lever, locking means for locking said controlling instrumentalities whereby to prevent release movement of the brake lever prior to reverse movement of the reverse lever, and releasing movement of the clutch lever when the brake lever is in release position.

32. In apparatus of the class described, the combination of a driven shaft, a cage actuating drum operable thereby, a plurality of controlling instrumentalities associated therewith including a brake lever, a reverse lever and a clutch lever, and locking means for locking said controlling instrumentalities whereby to prevent release movement of the brake lever prior to reverse movement of the reverse lever, and releasing movement of the clutch lever when the brake lever is in release position, and vice versa.

33. In apparatus of the class described, the combination of a driven shaft, a cage actuating drum operable thereby, brake control means, means for controlling reversal of the drum, and means associated with the brake control means aforesaid for preventing releasing movement of said brake control means until after operation of the reversing means.

34. In apparatus of the class described, the combination of a driven shaft, a cage actuating drum operable thereby, brake control means, means for controlling reversal of the drum, and means associated with the brake control means for automatically engaging therewith upon operation of said brake means to apply the brake, and release means operable by the reversing means for disengaging the engaging means for the brake control means to permit operation of the latter.

35. In apparatus of the class described, the combination of a driven shaft, a cage actuating drum operable thereby, a plurality of controlling instrumentalities associated therewith including a brake lever and a reverse lever, locking means associated with the brake lever and operable under the control of the cage to interlock with the brake lever when the latter is moved into brake setting position, and release means operable by the reverse lever for disengaging the locking means after reverse movement of the reversing lever whereby to permit release movement of the brake lever.

36. In apparatus of the class described, the combination of a driven shaft, a cage actuating member operable thereby, brake and clutch control instrumentalities, and means associated with the clutch control for preventing release of the brake control when the clutch control is in clutch releasing position.

37. In apparatus of the class described, the combination of a driven shaft, a cage actuating member operable thereby, brake and clutch control instrumentalities, and means associated with the brake control for locking said clutch control in clutch engaging position when the brake control is in released position.

38. In apparatus of the class described, the combination with a driven shaft and a

cage actuating element operable thereby, of
brake applying means, controlling mech-
anism for causing operation of the brake ap-
plying means incident to slippage or break-
age permitting relative movement of the
shaft and cage actuating element, and other
controlling mechanism for also causing oper-
ation of the brake applying means incident
to excessive speed of the cage actuating ele-
ment.

39. In apparatus of the class described,
the combination with a driven shaft and a
cage actuating element operable thereby, of
brake applying means, controlling mech-
anism for causing operation of the brake ap-
plying means incident to slippage or break-
age permitting relative movement of the
shaft and cage actuating element, other con-
trolling mechanism for also causing opera-
tion of the brake applying means incident
to excessive speed of the cage actuating ele-
ment, and actuating means common to both
controlling mechanisms.

40. In apparatus of the class described,
the combination with a driven shaft and a
cage actuating element operable thereby, of
brake applying means, operating means
adapted to control said brake applying
means, a slippage or breakage governing
control, an excessive speed governing con-
trol, and means intermediate said controls
and the operating means for causing opera-

tion of the brake applying means upon ab-
normal relative movement of the driven
shaft and cage actuating element. 35

41. In apparatus of the class described,
the combination of a driven shaft, a cage
operating element operable thereby, brake
applying means, a governor control, and
means associated with the governor control 40
for causing operation of the brake applying
means upon abnormal speed of the cage be-
tween landings, said means including means
compelling a reduction of speed as the cage
approaches a landing. 45

42. In apparatus of the class described,
the combination of a driven shaft, a cage
operating element operable thereby, brake
applying means, a governor control, means
associated with the governor control for au-
tomatically causing operation of the brake
applying means under excessive speed of the
cage when approaching a landing, and means
intermediate the governor control and the
last-mentioned means for operating the lat-
ter to permit of normal acceleration of the
cage upon leaving a landing. 50 55

In testimony whereof I affix my signature
in presence of two witnesses.

CHARLES E. McDONALD.
